UNITED STATES PATENT OFFICE.

LAWRENCE E. MELHUISH, OF GLEN RIDGE, NEW JERSEY, ASSIGNOR TO WESTERN ELECTRIC COMPANY, INCORPORATED, OF NEW YORK, N. Y., A CORPORATION OF NEW YORK.

VACUUM-TUBE SOCKET.

Application filed June 27, 1922. Serial No. 571,266.

To all whom it may concern:

Be it known that I, LAWRENCE E. MELHUISH, a citizen of the United States, residing at Glen Ridge, in the county of Essex, 5 State of New Jersey, have invented certain new and useful Improvements in Vacuum-Tube Sockets, of which the following is a full, clear, concise, and exact description.

This invention relates to vacuum tube 10 sockets.

An object of this invention is a vacuum tube socket adapted for mounting on a panel so that the tube is arranged substantially parallel to the panel.

15 Another object of the invention is to support the contact springs of a vacuum tube socket from one end of the socket and to isolate one of the contact springs from the others.

20 Another object of the invention is a vacuum tube socket wherein the contact springs are arranged to project through the panel upon which the socket is supported so that all the wiring may be concealed behind 25 the panel.

Referring now to the drawing:

Fig. 1 is a vertical section of the socket showing a vacuum tube base therein.

Fig. 2 is a plan view partially broken 30 away.

The socket comprises an apertured base plate 10, adapted to be attached to a panel. Integral with this plate and projecting from the aperture is an elbow 11 terminating in 35 a cylindrical shell 12 which is adapted to receive the base of a vacuum tube. A bayonet slot 13 is provided in the shell to receive the locking pin of a vacuum tube. To the rear wall of the base plate 10 is attached,

40 by means of the screws 14, a block 15 of insulating material which slightly overlies the aperture. A second block 16 of insulating material is also attached to the rear wall of the base plate 10 by means of the screws

45 17 and is arranged diametrically opposite the block 15. In the lower face of the block 15 are cut three grooves extending transversely of the block. Arranged in these grooves are the contact springs 18, 19 and

50 20 which are held in position by the bolts and nuts 21 and 22. These contact springs project into the elbow 11 and are arranged to contact with terminals of a vacuum tube when inserted in the socket.

A groove extends transversely of the upper 55 face of the block 16 and a contact spring 23 is held therein by the bolt and nut 24 and 25. This contact spring extends into the elbow portion beneath the other contact springs and is bent upwardly and rearwardly 60 to bring its end into position to be engaged by the anode terminal of a tube. The contact springs 18 and 19 are arranged to contact with the filament terminals of a tube and the contact spring 20 is arranged to engage 65 the grid terminal.

By virtue of the above described arrangement the filament and grid contact springs are comparatively widely separated, at all points, from the anode contact spring and 70 are therefore well insulated therefrom. Each of the contact springs is provided with a notch at its outer end to receive the wires by means of which the socket may be connected in any desired circuit.

75 A disc 27 of insulating material is supported at the lower end of the shell 12 on bosses 26 extending from the interior thereof. This insulating disc is provided with a plurality of apertures of proper size and arranged to permit the terminals of a vacuum tube base to pass therethrough and engage the contact springs. This plate prevents the possibility of the insertion within the socket of anything which might bridge two 80 of the contact springs and establish a short circuit, and also protects persons using it from accidentally touching the high voltage anode contact. Furthermore it serves as a means for limiting the use of this socket to 85 tubes having an arrangement of terminals 90 which will pass through the apertures.

What is claimed is:

1. In combination, a base plate having an aperture, an elbow extending from said plate and terminating in a shell, a plurality of contact members attached to the rear wall of said base plate, an additional contact member attached to said rear wall and isolated from the other contact members, each of said contact members projecting into said elbow portion, said isolated contact member lying in a plane other than said first contact members and being relatively widely separated therefrom.

100 105 2. A vacuum tube socket comprising an elbow terminating in an apertured base plate, strips of insulating material attached

to the rear face of said base plate, a plurality of contact members carried by said insulating strips and projecting into said elbow, one of said contacts lying in a different plane from said other contacts and having its free end in the same plane of said other contacts.

3. A vacuum tube socket comprising an elbow having one end terminating in a base plate and the other end terminating in a cylindrical shell, a pair of insulating strips attached to the rear wall of said base plate and arranged substantially diametrically opposite each other, a plurality of contact members carried by one of said strips and projecting into said elbow, and a single contact member carried by the other insulating strip, said last named contact member projecting into said elbow and having its inner end offset to bring it into the plane of the other contact members.

4. A vacuum tube socket comprising an elbow terminating in a base plate, a pair of strips of insulating material attached to the rear wall of said base plate at opposite points thereof, a plurality of contact members carried on one of said strips and projecting into the said elbow, a single contact member carried by the other of said strips, the inner end of said last named strip being provided with a return bend to bring its end into the same plane with the first named contacts.

5. A vacuum tube socket comprising an elbow terminating in a base plate, a plurality of contact members attached to said base plate and arranged in the same plane, and another contact member attached to said base plate in a different plane from said first contact members, said last named contact member having its inner end offset to bring it into the same plane as the ends of the other terminals.

6. A vacuum tube socket comprising a base plate, a shell supported by said plate with its axis parallel to the plane of said plate, a pair of insulating strips positioned at opposite points on the rear wall of said plate, a plurality of contact springs carried by one of said strips and projecting within said shell and another contact spring carried by the other of said strips and projecting within said shell, the end of said last-named contact spring being offset to bring it into the plane of the other contact spring.

7. A vacuum tube socket comprising a base plate, a shell supported by said plate with its axis parallel to the plane of said plate, a pair of insulating strips mounted on the rear wall of said plate diametrically opposite each other, a plurality of contact springs mounted on one of said insulating strips and projecting within said shell, an additional contact spring carried by the other insulating strip and projecting within said shell, the end of said last named contact spring being offset to bring it in the plane of the other contact springs, and an insulating plate carried by said shell in proximity to the ends of said contact springs, said disc having a plurality of apertures through which may be inserted the terminals of a vacuum tube to engage said contact springs.

8. A vacuum tube socket comprising a base, a tubular member arising therefrom, a plurality of contact members insulatingly supported at one end of the base and projecting across one end of said tubular member, one of said contact members being mounted in a different plane from the others but having its free end in the same plane.

In witness whereof I hereunto subscribe my name this 23rd day of June, A. D., 1922.

LAWRENCE E. MELHUISH.
